UNITED STATES PATENT OFFICE.

LOUIS M. BOYLE, OF LOS ANGELES, CALIFORNIA.

CAMP STOVE.

Application filed January 8, 1921. Serial No. 435,937.

To all whom it may concern:

Be it known that I, Louis M. Boyle, a citizen of the United States, residing at Los Angeles, county of Los Angeles, and State 5 of California, have invented a new and useful Improvement in Camp Stoves, of which the following is a specification.

An object of my invention is to provide a camp stove which may be used without stove- 10 pipe, but in which an efficient draft may be maintained.

A further object of my invention is to provide a camp stove in which the products of combustion may be discharged directly 15 against the cooking utensils to be heated and at the same time maintain an efficient draft.

A further object of the invention is to provide a very rigid top structure to which are rigidly attached sturdy legs, so that the 20 whole stove is substantial and may be placed on uneven ground and sustain heavy loads without distortion.

A still further object of the invention is to provide a novel form of top which may be 25 used as a skillet and which is also provided with a grid upon which meat may be broiled or cooking utensils supported.

A still further object of the invention is to provide a novel form of grid which will not 30 warp even when subjected to great heat.

Further objects and advantages will be made evident hereinafter.

Referring to the drawings which are for 35 illustrative purposes only,

Fig. 1 is a perspective view of the stove in position to be used.

Fig. 2 is a section on a plane represented by the line 2—2 of Fig. 1 on an enlarged scale.

Fig. 3 is a section thru one end on a plane represented by the line 3—3 of Fig. 1.

Fig. 4 is a section thru one of the corners with a leg in place on a plane represented by the line 4—4 of Fig. 1.

Fig. 5 is a perspective view of the upper end of one of the legs.

Fig. 6 is a section on a plane represented by the line 6—6 of Fig. 1.

Fig. 7 is a section thru one of the 50 corners on a plane represented by the line 7—7 of Fig. 4.

In the form of the invention shown, a top 11 is provided, this top being formed of sheet metal which is turned over to form an 55 apron 12 extending therearound and having a rolled edge 13. Each of the corners of

the apron is reinforced by a member 14. The top 11 has two portions, namely, a depressed imperforate portion 15 which is used as a skillet, all kinds of cooking being done 60 directly thereupon and a grid 16 formed in the top adjacent to the skillet 15, the grid 16 being formed by cutting out portions of the metal to form perforations 17, a portion of this metal being rolled in the form shown 65 at 18 in Fig. 2 to form cylindrical tubular bars which extend across the top 11 between the perforations 17. These tubular bars are open at either end. Secured in each of the corners of the stove is an angle iron leg 20, 70 the upper portion of these legs having the form shown in Fig. 5, the edges of the angle irons being bent in as shown at 21, leaving a square corner portion 22. The portion 22 fits inside a strap 23 secured by rivets 24 in 75 the corner of the apron 12 as shown in Fig. 7, the portions 21 fitting outside this strap thus very securely locking each of the legs 20 in place. To prevent the legs from being lost, each of them is secured by a chain 25 80 shown in Fig. 4 to a portion of the top 11. Detachably secured in each side of the stove is a side member 30 formed of sheet metal and having two hooks 31 passing thru holes 32 in the aprons 12. An end member 85 33 is similarly secured in the end adjacent to the grid 16.

The method of operation of the invention is as follows:

The stove being set up as shown in Fig. 1 90 with the members 30 and 33 in place it forms a box open at the end adjacent to the skillet 15 and closed on either side and on the end adjacent to the grid 16. A wood fire being built in this space is supplied with air 95 thru the end of the box, the perforations 17 acting as a vent thru which the smoke can escape. With a brisk wood fire, inside the stove, there is a great concentration of heat passing upwardly between the bars 18 100 of the grid 16 and at the same time the skillet 15 is very rapidly heated. Cooking utensils may be placed upon the bars 18 and very quickly heated and the skillet 15 may be used directly for cooking. The form of the cylindrical tubular bars 18 is such that they may be subjected to great heat without distortion.

Whenever it is desired to dismantle the stove for transportation, the sides 30 and 110 the end 33 are removed which can be readily done by lifting the lower edges and pulling

outwardly thereon. The legs 20 can then be pulled out of the sockets formed by the strap 23 and the apron 12 and the sides, end, and legs may all be packed inside the apron 12 against the under side of the top 11. A canvas bag may be provided into which the stove may be slipped when not in use.

I claim as my invention:

1. In a stove a grid comprising a single sheet of metal having perforations extending across the sheet, a portion of the material punched out of said perforations being bent under to form cylindrical tubular bars extending across said sheet between said perforations.

2. In a stove a grid comprising a single sheet of metal having perforations extending across the sheet, a portion of the material punched out of said perforations being bent under to form cylindrical tubular bars open

at either end extending across said sheet between said perforations.

3. A top for a stove comprising: a sheet of metal having its edges turned at right angles to the top of said sheet to form a continuous apron therearound; and bars extending across a grid opening in said sheet.

4. A top for a stove comprising a single sheet of metal having a portion imperforate to form a skillet and a portion having openings cut therein to form a grid.

5. A top for a stove comprising a single sheet of metal having an imperforate skillet portion, said top having a series of parallel openings therein to also form a grid.

In testimony whereof, I have hereunto set my hand at Chicago, Illinois, this 2nd day of December, 1920.

LOUIS M. BOYLE.
